US0D1103132S

(12) **United States Design Patent** (10) **Patent No.:** **US D1,103,132 S**
(45) **Date of Patent:** **** Nov. 25, 2025**

(54) **COMBINED COMPOSITE FILM AND
INSTALLATION SYSTEM FOR
ELECTRONIC PRODUCTS**

(72) Inventor: **Qiang Xiong**, Shenzhen (CN)

Primary Examiner — Derrick E Holland

(73) Assignee: **SHENZHEN ABEE TECHNOLOGY
CO., LTD**, Shenzhen (CN)

(74) *Attorney, Agent, or Firm* — United IP Counselors,
LLC

(**) Term: **15 Years**

CLAIM

(21) Appl. No.: **29/870,396**

(22) Filed: **Jan. 25, 2023**

(30) **Foreign Application Priority Data**

Dec. 9, 2022 (CN) 202230827684.8

DESCRIPTION

(51) **LOC (15) Cl.** **13-99**

FIG. 1 is a front perspective view of a combined composite film and installation system for electronic products showing the new design;

(52) **U.S. Cl.** **D13/199**

FIG. 2 is a back perspective view;

USPC **D13/199**

FIG. 3 is a front elevational view;

(58) **Field of Classification Search**

FIG. 4 is a back elevational view;

USPC D13/101, 118, 179, 182, 184, 199;

FIG. 5 is a left elevational view;

D24/231

FIG. 6 is a right elevational view;

CPC H01R 13/514; H01R 13/6586; H01R

FIG. 7 is a top plan view; and,

13/6587

FIG. 8 is a bottom plan view.

See application file for complete search history.

In the drawing figures, the indicia shown in broken lines
form no part of the claim.
